UNITED STATES PATENT OFFICE.

JOSEPH WADLEIGH, OF MILKS GROVE, ILLINOIS.

HAY-PRESS.

SPECIFICATION forming part of Letters Patent No. 276,649, dated May 1, 1883.

Application filed February 13, 1883. (No model.)

To all whom it may concern:

Be it known that I, JOSEPH WADLEIGH, of Milks Grove, in the county of Iroquois and State of Illinois, have invented new and useful Improvements in Hay-Presses, of which the following is a specification, reference being had to the accompanying drawings, illustrating the invention, in which—

Figure 1 is a plan or top view of a pressing-box and a power embodying my invention; Fig. 2, a side elevation thereof, with the side of the press removed, more clearly to show the internal parts. Fig. 3 is a vertical section of the power-wheel. Fig. 4 shows the chain and its pitman attachment removed from the pitman and power-wheel.

The object of the present invention is to provide a power-press which is suitable to press hay, cotton, straw, brick, and other material, which shall be simple, cheap, durable, and efficient, and adapted to horse-power.

The nature of the invention consists of a power-wheel whose periphery is grooved to carry a chain which is attached thereto and to a pitman, so that the pitman will be operated when the power-wheel is turned in either direction and give to the plunger a movement one-fourth (or less) greater than the diameter of the power-wheel, whereby the pitman is not thrown so much obliquely to the press-box as when the pitman is journaled to the wheel by a wrist-pin; and, further, in a tenon attachment to the chain, which is fitted in a mortise in the wheel end of the pitman, so as to be removed for the convenience of removing the chain for repairs, as the whole is hereinafter fully described and shown.

A B represent the frame of the press-box, and E represents the box. C D represent the frame which supports the power-wheel J, attached to the frame A B in a substantial manner. This frame, however, may have any form which will hold the working parts relatively in position with the press-box.

J represents the power-wheel, which is, by means of a pivot-shaft, K, hung to the frame D, an iron box, M, being employed for that purpose, as shown at Fig. 2. The height of this wheel corresponds to the height of the pitman G, which is jointed to the middle part of the plunger F of the press-box E, as shown

at H. The end of the pitman opposite to the power-wheel is strengthened with a metal plate, I, preferably of steel, and through this plate and into the end of the pitman G is formed a mortise, R, to receive the chain attachment V, as shown at the enlarged Fig. 4, the top portion of the end of the pitman being broken away at T to give a plan view of the mortise. The end of the tenon or chain attachment V is provided with an eye, e, to which the link of the chain c is secured in the ordinary manner. This chain may be formed with square links, as shown, or oblong links; but in either event the periphery of the wheel J should be formed, as shown, with an annular groove, P, to receive the edges of the horizontal links, and rabbits N N, to receive the vertical links, in order that the chain may have a smooth and properly-seated bearing, to prevent breakage and unnecessary wear. The chain c, to give a movement to the plunger F a one-fourth greater than the diameter of the wheel J, should be attached to the wheel at a point, x, Fig. 1, and the pitman should be about two and one-half times as long as the diameter of the wheel. A pitman of less length will answer the purpose, when used with the chain and wheel, to give a sudden return to the plunger F by the elasticity of the material in the box to be pressed, but will not allow the plunger to pass so far as is sometimes required to admit of a speedy filling of the press with material. A material advantage of this construction is that the chain c has only to stand the strain during the time when the lesser pressure is required. When the greater pressure is required, the wheel end of the pitman is brought onto the periphery of the wheel, as shown at Fig. 1, at which point the chain is not subjected to any strain. The wheel J and pitman G are shown in position as when the plunger F has the greatest throw into the box E. The dotted lines L e c m J represent the pitman, chain, eye, chain-wheel, and plunger in position after the pitman has passed the point of greatest pressure, and has been made to rebound by the elastic material in the box. n n (dotted lines) show the reverse position of the sweep b where the pitman is thrown to the opposite side of the press-frame. By this means a very simple, convenient horse-power press is provided,

of sufficient strength to press both cotton and hay, also like material; or it may be used to press material less elastic.

It is well to state, with reference to durability, that the periphery of the wheel J at *ff* may be banded with steel, so as to attain strength. Where non-elastic material is pressed the plunger can be suddenly returned by a weight or a spring.

10 I claim as new—

1. In hay-presses and presses for compacting like material, the power-wheel J, constructed and hung substantially as shown and

described, in combination with the chain *c*, pitman G, and plunger F, for giving a double rebound movement to the plunger, as and for the purpose specified.

2. The pitman G of a hay-press, combined with the chain attachment V, tenoned into the pitman, as specified, the wheel J, chain *c*, and plunger F, as and for the purpose specified.

JOSEPH WADLEIGH.
